BANK ACCOUNT EXPEDITER

Raymond E. Bauder, Chicago, Ill.

Application March 18, 1943, Serial No. 479,652

4 Claims. (Cl. 129—16.7)

The invention aims to provide a novel and advantageous visible filing device for expediting the handling of depositors' accounts at banks, and in carrying out this end, further objects are to provide for quick and easy inspection of checks drawn on any account and accurate comparison of the check signatures with the specimen signature on a novel signature card kept by the bank; to provide a convenient folder attached to the signature card to retain all examined checks (and preferably deposit slips also) relating to the account of the person whose signature appears on said signature card, and to form said folder from a sheet detachably connected with said signature card and adapted to constitute a monthly statement to be detached and mailed to the depositor.

With the foregoing in view, the invention resides in the novel device hereinafter fully described and claimed, description being accomplished by reference to the accompanying drawings.

Figure 1 is a front elevation.

Fig. 2 is an enlarged sectional view on line 2—2 of Fig. 1.

Fig. 3 is a sectional view on line 3—3 of Fig. 2 with the front portion of the folder unfolded.

Figs. 4, 5 and 6 are perspective views showing not only structural characteristics of the device but preferred ways of using the same.

A preferred construction has been illustrated and will be specifically described, with the understanding, however, that within the scope of the invention as claimed, variations may be made. Moreover, while the description will refer to the account of an individual, it is to be understood that the same structure may be employed for joint accounts, for accounts in which a second person may sign if necessary in place of the usual person signing checks, and for the accounts of various kinds of firms or business establishments.

A visible filing card 10 is provided having a folded-over head bar 11 at its upper end, said head bar and the subjacent portions of the card projecting laterally to provide ears 12 for reception in guide grooves along the edge portions of a shallow filing tray (not shown). The lower edge of the head bar 11 is provided with tongues 13 extending through slots or slits 14 (Fig. 2) in the card 10, said tongues diverging with respect to said card so that the tongues of any filing card 10 may hook over the upper portion of the subjacent card in the filing tray, leaving the lower portions of the various cards readily visible.

The card 10 and the structural features 11 to 14 associated therewith are disclosed and claimed in my U. S. application Serial No. 475,119, filed February 8, 1943. This application also discloses a form of filing tray with which the cards forming part of the present invention may be used.

Along its lower end, the card 10 is provided with an area 15 to display a specimen signature of the person to whose account the card relates, there being preferably a line 16 printed on the card as a guide in writing the signature. Should the account be such that checks may be drawn by more than one person, the necessary additional signature or signatures would be placed 15 on the area 15 and it is, therefore, obvious that other guide lines, such as 16, could be employed, if desired. This area also preferably includes a "station" 17 for the depositor's account number, and his name and address are preferably conspicuously typed on said area below the specimen signature.

A folder 18 of flat form lies upon the front of the file or signature card 10 and has its lower edge 19 disposed along the upper margin of the 25 signature area 15. The dimension of this folder from its upper to its lower edge is thus somewhat less than the corresponding dimension of the card 10, but said dimension of said folder is preferably a trifle greater than the dimension 30 of a conventional check measured from the upper to the lower edge.

Any check relating to the account may be initially placed upon the folder 18 as seen in Fig. 4, and the same is true of any deposit slip, a check being indicated at 20 in this and other views and a deposit slip at 21. The checks and deposit slips may be left in this position until reached for inspection as to signature, post dating, etc. Any check thus visibly laid upon the folder 18 will 40 have its signature directly above the specimen signature on the card 10 as seen in Fig. 4, for convenient and accurate comparison of said check signature with said specimen signature. After inspection and signature comparison, the 45 check may be placed in the folder 18 as seen in Fig. 5, and all deposit slips after proper examination are also placed in this folder. If desired, the checks and deposit slips may be offset to the right as seen in Fig. 5 when they are placed in 50 the folder 18, to signify something relating to them, for example, that they have been examined. In this offset-to-the-right position, all essential data on the checks is accessible, such as account number, amount and signature. If desired, when 55 the checks are placed in the folder 18, they may

be offset to the left to indicate something relating to them, for instance, that they have not been examined. Thus, even in a well filled filing tray, items may be instantly "spotted" and it becomes unnecessary to touch the cards of other accounts, as would be the case were all items (examined and not examined) sorted without respect to such offsetting. In other applications of the invention, this offsetting of items to right and/or left might well indicate, for example, (1) items posted and (2) items not posted, etc. Banks generally post their checking accounts two or three times a day, as otherwise they would have difficulty in determining the "present" status of each account. Ordinarily, if a check should be presented and questioned, piles of checks and deposit slips representing all accounts and unposted transactions to the moment must be fingered to determine the available balance. When using the present invention, however, say with all unposted items in juxtaposition, the operation is greatly facilitated, particularly when the folder 18 is formed from a sheet to constitute a monthly statement sheet to be sent to the depositor, as is preferable. When such a monthly statement sheet is employed in forming the folder 18, deposits and withdrawals are entered on the sheet (see Fig. 3). Whenever a deposit slip is examined and placed in the folder, a notation is made on the sheet as to the amount of the deposit. Similarly whenever a check is examined and placed in the folder, the account is debited accordingly on the sheet. Thus, it is only a matter of moments to determine the "present" standing of any account.

The sheet forming the folder 18 is denoted at 22, the dimension of said sheet from its upper to its lower end (see Fig. 3) being considerably greater than the corresponding dimension of the card 10, providing ample space on one or both sides of said sheet for various entries. The upper end of this sheet 22 is connected with the card 10 by passing the tongues 13 through slots or slits 23 in said upper end. While two of these slots or slits 23 are shown, and the head bar 11 has two tongues 13, the invention is not concerned with number. In fact, the present application is not concerned with any particular way of attaching the sheet 22 to the card 10, and the specific attaching means shown is disclosed in the application above referred to.

When the preferred construction, herein disclosed, is followed, with the folder or pocket 18 formed from a sheet 22 constituting a monthly statement sheet to be detached and sent to the depositor, one fold of said sheet substantially at its center will suffice, the line of fold constituting the lower end of the pocket or folder as hereinbefore identified at 19. The upwardly folded half of the sheet 22 forms a flat support upon which checks and the like may be placed in readiness for examination as seen in Fig. 4 and also in Fig. 6. In the latter view, a check 20 and deposit slip 21 shown resting upon the folder 18 in Fig. 4 have been placed within said folder as illustrated also in Fig. 5, and another check 20^a has been laid upon said folder in readiness for examination.

From the foregoing, taken in connection with the accompanying drawings, it will be seen that novel and advantageous provision has been made for carrying out the objects of the invention, and while preferred details have been disclosed, attention is again invited to the possibility of mak-

ing variations within the scope of the invention as claimed.

I claim:

- 5 1. A bank account expeditor comprising a file card to be kept by a bank, said file card having an area along its lower edge upon which the signature of a bank depositor may be written, and a flat folder for retaining checks drawn by said depositor, said folder being attached to said card and having its lower edge disposed along the upper margin of said signature area, whereby any check drawn on said account may be laid on said folder for inspection and accurate comparison of the check signature with the subjacent signature on said signature area of said card, and all examined checks may be retained in said folder, the right and left ends of said folder being open to permit checks in said folder to project indicatively beyond either end thereof.
- 10 2. A structure as specified in claim 1; said folder and card having separably engaged connecting means detachably connecting said folder with said card, said folder being ruled and constituting a statement blank for the depositor's account.
- 15 3. A bank account expeditor comprising a file card to be kept by a bank, said card being of greater dimension from its upper to its lower edge than the corresponding dimension of a conventional bank check, said card having an area along its lower end upon which the signature of a depositor having an account at said bank may be written, a sheet lying upon said card, said sheet being of considerably greater dimension from its upper to its lower end than the corresponding dimension of said card, and means connecting the upper end of said sheet with the upper end of said card, substantially the lower half of said sheet being upwardly folded onto the upper half along a fold line at the upper margin of said signature area of said card and constituting a flat support upon which to lay any check drawn on said account for inspection and accurate comparison of the check signature with the subjacent signature on said signature area of said card, said folded sheet constituting a pocket in which to retain the various checks after inspection and signature comparison, said lower half of said sheet being free of connection with said upper half except along said fold line, to permit checks in said pocket to project indicatively beyond either end thereof.
- 20 4. A bank account expeditor comprising a file card to be kept by a bank, said card being of greater dimension from its upper to its lower edge than the corresponding dimension of a conventional bank check, said card having an area along its lower end upon which the signature of a depositor having an account at said bank may be written, a ruled statement sheet lying upon said card upon which entries relating to the account may be written, said statement sheet being of considerably greater dimension from its upper to its lower end than the corresponding dimension of said card, and separably engaged connecting means on said card and said statement sheet detachably connecting the upper end of said statement sheet with the upper end of said card to permit easy detachment and mailing of said statement sheet to the depositor and permit easy substitution of a duplicate sheet for the next statement, substantially the lower half of said statement sheet being upwardly folded onto the upper half along a fold line at the upper margin of said signature area of said card and constitut-

ing a flat support upon which to lay any check drawn on said account for inspection and accurate comparison of the check signature with the subjacent signature on said signature area of said card, said folded statement sheet constituting a pocket in which to retain the various checks after inspection and signature comparison, said lower half of said statement sheet be-

ing free of connection with said upper half except along said fold line, to permit checks in said pocket to project indicatively beyond either end of said pocket and to permit said sheet to be unfolded and laid flat to facilitate making entries upon it.

RAYMOND E. BAUDER.
